UNITED STATES PATENT OFFICE.

ALBERT B. COLLINGBOURNE, OF CHICAGO, ILLINOIS.

DESIGN FOR A TATTING-SHUTTLE.

47,811.

Specification for Design.

Patented Sept. 14, 1915.

Application filed June 28, 1915. Serial No. 36,870. Term of patent 3½ years.

To all whom it may concern:

Be it known that I, ALBERT B. COLLINGBOURNE, a citizen of the United States, and a resident of the city of Chicago, county of Cook, and State of Illinois, have invented a new, original, and ornamental Design for Tatting-Shuttles, of which the following is a specification, reference being had to the accompanying drawing, forming part thereof.

In the accompanying drawings, Figure 1

represents a view in perspective of my novel tatting shuttle design, and Fig. 2 represents a top plan view thereof.

I claim:

The ornamental design for a tatting shuttle, as shown.

ALBERT B. COLLINGBOURNE.

Witnesses:

T. H. ALFREDS,

KARL W. DALL.
